FIG. III.

FIG. V.

INVENTOR:

ALBERT LINDSAY DOERING,

By *Arthur E. Paige*,
Attorney.

Patented Mar. 5, 1929.

1,704,560

UNITED STATES PATENT OFFICE.

ALBERT LINDSAY DOERING, OF GERMANTOWN, PENNSYLVANIA.

CASEMENT FASTENER.

Application filed March 26, 1928. Serial No. 264,759.

My invention relates to devices for fastening a casement window sash in closed position in its window frame, so as to maintain the same in tight weather-proof relation except when said device is released to permit the sash to be swung open, and my device is of what is known to the trade as the cam handle class, i. e., including means for effecting a cam action whereby the sash is drawn into tight relation with the window frame.

Ordinary devices for the purpose aforesaid include a handle pivoted upon a rivet which is intended to be a fixture in a base plate primarily separate and distinct from both the sash frame and the window frame but having openings, in said plate, through which the plate may be connected with the sash frame by screws or rivets. In all such devices, the stresses incident to closing the sash and holding it in closed position are such as to continually tend to loosen the rivet holding the handle to the plate, and the screws or rivets holding the plate to the sash frame. Moreover, the movement of the handle is only limited by a projection on said plate, which is independent of both the sash and the handle and does not prevent the handle from being turned into such position that it interferes with the opening movement of the sash when the handle is unfastened and the sash otherwise free to be opened. Ordinarily, such devices are unyielding and are so constructed and arranged that although primarily firmly operative, they rapidly deteriorate until they are loose and practically inoperative.

Therefore, it is the purpose and effect of my invention to provide a fastening device for the purpose above described adapted to maintain the sash frame closed in its window frame under resilient pressure and to maintain itself continuously in operative relation.

As hereinafter described, my invention is so constructed and arranged that the handle pivot is carried by the handle and extends between parallel leaves on the handle which resiliently embrace between them a pivotal support which is in unitary or integral relation with the sash frame; so that the stresses incident to closing the sash and holding it closed are resiliently borne by the pivot member of the sash without tendency to loosen the pivot in the handle. Moreover, the bight between said handle leaves is so shaped in relation to the pivot member on the sash frame as to limit the movement of the handle to and from operative position; without require-

ment of the projection or other means for that purpose as in the old devices aforesaid; so that it is impossible to place the handle in position to interfere with the opening movement of the sash, when it is released.

My invention includes the various novel features of construction and arrangement hereinafter more definitely specified.

In said drawings; Fig. I is an inside elevation of a casement sash, and window frame, embodying my invention.

Fig. II is a fragmentary plan sectional view of the sash frame and window frame, taken on the line II, II in Fig. I, and showing a plan view of the fastener in closed position.

Fig. III is a fragmentary elevation of the sash, with the handle in section, taken on the line III in Fig. II.

Fig. IV is a sectional view of a window frame and sash frame showing a modified form of pivot member on the latter.

Fig. V is a fragmentary elevation of the structure shown in Fig. IV.

Fig. VI is a fragmentary vertical sectional view taken on the line VI in Fig. II and showing the closed relation of the movable cam arm on the sash frame with the stationary cam block on the window frame.

In said figures; 1 is the window frame which is rigidly set in the building wall in any convenient manner, and is provided with hinges 3 by which it is pivotally connected with the sash frame 2 which is thus mounted thereon to swing outwardly.

In the form of my invention shown in Figs. II and III, both the window frame 1 and sash frame 2 are formed of rolled steel bars of the same cross section, including central webs having wide and narrow flanges upon respectively opposite sides thereof. However, as shown in Fig. II, the position of the bars is reversed in the two frames so that the wide flange of each overlaps the narrow flange of the other, forming what are termed weathering joints, i. e., contact surfaces which are substantially water-tight, at 5 and 6.

As shown in Fig. II, the sash frame 2 is provided with the unitary pivot bearing member 8 which is a plate of the same thickness as the flange 9 on said frame 2 and offset inwardly, with respect to the window frame, in integral relation with the inner edge of said flange 9. Such a bearing member 8 is conveniently formed from a primarily separate plate which is fitted in the frame 2 where

a portion of the flange 9 has been removed, and is welded in flush relation with the flange 9 at the places indicated by the dotted lines 10 in Fig. III.

5 As shown in Figs. IV and V, the pivot bearing member 8 on the sash frame 2 is formed of a primarily separate plate which is fitted in place of a portion of the flange 9 of the frame 2 which is cut to receive it and is welded in 10 flush relation with said flange 9 at the joints indicated by the dotted lines 11 in Fig. V. However, the outer end of such plate is bent parallel with the web of the frame 2 as indicated at 12 in Fig. IV and may be welded, 15 riveted or otherwise rigidly connected therewith.

In each form of my invention above described, the inner edge 14 of the pivot bearing plate 8 is semi-circular but in eccentric relation to the pivot bearing 15, which is a hole drilled therethrough at right angles to said plate and to the plane of the sash frame 2. As shown in Fig. II, the cam handle is a lever having the arm 17 adapted to be manually gripped, and has parallel leaves, or jaws, 18 and 19 fitted to embrace between them the bearing pivot plate 8. Said leaves are connected by the bight 20 and have the primarily plane recess 21 between them, conveniently 25 formed by a milling cutter so as to fit easily upon said pivot plate 8. However, the pivot screw 23 which extends between said primarily parallel leaves 18 and 19 and is the fulcrum pivot for said lever, extends through the 30 smooth bearing 24 in the leaf 18 but is in screw threaded engagement with the bearing 25 in the leaf 19 and is screwed tight enough to frictionally engage said pivot bearing member 8 on the sash frame 2 and prevent rattling of the handle 17 in connection therewith. I find it convenient to lock said pivot screw 23 in adjusted position in the handle by 40 means of the lock washer 26 beneath the head of the screw which engages the latter and the opposite surface of the handle leaf or jaw 18. However, said lock washer 26 may be omitted if the screw 23 tightly engages the thread in the bearing 25. In any case, the pivot screw 23 normally remains in stationary relation 45 with the handle 17 and its adjustment is not disturbed by any of the stresses incident to the use of the fastening device.

Said handle jaw 18 carries the radially extending cam arm 28 which may be primarily 55 bent toward the window frame 1 at an angle of about five degrees to the plane of said frame, and has a rounded surface presented toward the window frame 1, as indicated at 29 in Fig. VI, so as to ride easily upon the cam block 30 which is conveniently formed of a bronze casting having rivet lugs 31 with which it is rigidly connected with the window frame 1.

It is to be understood that the construction 60 and arrangement above described are such

that when the cam handle 17 is turned to the position indicated in dotted lines in Fig. I, the sash frame 2 may be swung upon its hinges 3 to open the casement; but, when the sash frame 2 is swung into closed position 70 with respect to the window frame 1, as indicated in Fig. II; the handle 17 may be turned to the position shown in full lines in Fig. I and, in so turning, encounters the inclined surface 32 of the cam block 30 before it 75 reaches the position shown in Fig. VI and is only brought into that position by resilient flexure of the entire fastening structure including the pivot bearing flange 8; so that, in the position shown in Fig. II, the two 80 frames are resiliently clamped together in water-tight relation.

Although I have shown the handle 17 as a straight cylindrical bar; it may be made of any convenient form and be ornamented, and although I have found it convenient to make such handles of wrought steel, they may be made of other material, for instance, cast bronze, and although I have found it convenient to form the recess 21 by milling operation; it may be formed by drop forging or die casting operation, or otherwise.

Therefore, I do not desire to limit myself to the precise details of construction and arrangement herein set forth, as it is obvious 95 that various modifications may be made therein without departing from the essential features of my invention, as defined in the appended claims.

I claim:

1. A cam lever for a casement fastener, including a handle adapted to be manually gripped, and having, in unitary relation therewith, two substantially parallel jaw leaves, with respective fulcrum pivot bearings, in coaxial relation; their common axis being at right angles to the plane of said leaves; said leaves being connected by a bight at one side thereof; and one of said leaves having a cam arm projecting from the opposite side thereof.

2. The combination with a cam lever as in claim 1; of a pivot bearing plate embraced between said jaw leaves; and a fulcrum pivot member, carried by said lever, in rigid relation therewith, and extending between said jaw leaves, through said plate; said bight being so constructed and arranged as to limit the turning movement of said lever relatively to said bearing plate, by encountering the latter.

3. The combination with a cam lever for a casement fastener, including a handle adapted to be manually gripped, and having, in unitary relation therewith, two substantially parallel jaw leaves, with respective fulcrum pivot bearings, in coaxial relation; their common axis being at right angles to the plane of said leaves; said leaves being connected by a bight at one side thereof; and

- one of said leaves having a cam arm projecting from the opposite side thereof; of a pivot bearing plate embraced between said jaw leaves; and a fulcrum pivot member, carried by said lever, in rigid relation therewith, and extending between said jaw leaves, through said plate; said plate being carried by a sash frame; a window frame to which said sash frame is hingedly connected; and an inclined cam block on said window frame, in cooperative relation with said cam arm on said lever; whereby said sash frame may be held in tightly closed position in said window frame; said bight being so constructed and arranged as to limit the turning movement of said lever relatively to said bearing plate, by encountering the latter. 35
5. The combination with a cam lever for a casement fastener, including a handle adapted to be manually gripped, and having, in unitary relation therewith, two substantially parallel jaw leaves, with respective fulcrum pivot bearings, in coaxial relation; their common axis being at right angles to the plane of said leaves; said leaves being connected by a bight at one side thereof; and one of said leaves having a cam arm projecting from the opposite side thereof; of a pivot bearing plate embraced between said jaw leaves; and a fulcrum pivot member, carried by said lever, in rigid relation therewith, and extending between said jaw leaves, through said plate; said plate being carried by a sash frame, and in resilient unitary relation therewith. 40
